UNITED STATES PATENT OFFICE.

LEROY W. BALDWIN, OF NEW YORK, N. Y.

DESIGN FOR A DIAL-FACE.

SPECIFICATION forming part of Design No. 32,683, dated May 22, 1900.

Application filed April 26, 1900. Serial No. 14,510. Term of patent 14 years.

To all whom it may concern.

Be it known that I, LEROY W. BALDWIN, a citizen of the United States, residing at New York, in the county of New York and State of New York, have invented and produced a new and original Design for Dial-Faces, of which the following is a specification, reference being had to the accompanying drawings, forming part thereof.

- 10 My invention relates to dials or dial-faces in general, and is more specifically intended for use on the dials of automatic weighing-machines for the purpose of rendering the same attractive to the eye and presenting different sections of the dial-face with different degrees of prominence.

The drawing represents a face view of a weighing-machine dial, showing my new design.

- 20 As shown in the drawing, the leading feature of my design is a half-circular space A of dark color (shown in the drawing in solid black) occupying one-half of the interior space of the dial-face B, which is of a con-

trasting color. (Shown in the drawing as 25 white.) The dial-face has a graduated outer circle C and a central perforation D for the passage of the shaft supporting the index-hand. (Not shown.) In the dark half-circle I outline in a contrasting color (shown in the 30 drawing as white) a series of rectangular panels so combined as to form a larger panel, substantially as shown.

It is apparent that this design is also applicable to timepieces and other instruments 35 having dial-faces.

Having therefore described my invention, what I claim as new, and desire to protect by Letters Patent, is—

The design for a dial-face as herein shown 40 and described.

Signed at New York, N. Y., February 9, 1900.

LEROY W. BALDWIN.
